UNITED STATES PATENT OFFICE

RALPH R. ROOT, OF LAKWOOD, OHIO, ASSIGNOR TO THE ROOT MANUFACTURING COMPANY, OF CLEVELAND, OHIO, A CORPORATION OF OHIO

DUSTER

Application filed October 24, 1930. Serial No. 490,967.

This invention relates to dusters, and more particularly to devices of this character adapted to be carried over a field for distributing insecticides and the like.

5 Dusters heretofore employed for this purpose have been unsatisfactory in that they have permitted leakage of the dust. The nature of the dust is such that it is uncomfortable, annoying, and injurious to the operator. It is therefore an object of the present invention to provide a duster in which the leakage is reduced to the extent of substantial elimination.

In dusting small plants, forward delivery 15 is essential in order that the operator may see to direct the dust to the individual plants, but when the plants are larger and more dense, it is desirable to distribute a larger cloud, and for this purpose a rearward delivery is preferred, in order that the operator may not breathe the dust. It is therefore a further object of the invention to adapt the duster for either forward or rearward delivery.

25 Various dusts for different purposes should be applied at definite rates of weight per acre. It is therefore another object of the invention to provide a device of this character which is accurately adjustable over a wide range to adapt the same for different rates and different weights, but which, when adjusted, will maintain the given rate substantially constant.

Still another object of the invention is to 35 provide a device of this character in which the drive mechanism is detachable as a unit,

Further objects are to simplify and improve the construction and operation of devices of this character, to render the same 40 economical to manufacture, substantially foolproof, and not likely to get out of order.

Other objects and features of novelty will be apparent as the following description proceeds, reference being had to the accompanying drawings in which:

Figure 1 is a side elevation of a duster according to the preferred embodiment of the present invention;

Fig. 2 is a plan of the structure shown in 50 Fig. 1;

Fig. 3 is a partial front elevation;

Fig. 4 is a partial vertical section taken along the line 4—4 of Fig. 1;

Fig. 5 is an elevation of the drive unit, showing the unit detached from the hopper; 55

Fig. 6 is an enlarged partial section taken along the line 6—6 of Fig. 5; and

Fig. 7 is a section along the line 7—7 of Fig. 4.

Referring more particularly to the drawings, the duster comprises a hopper 10, preferably constructed of sheet metal in substantially cylindrical form. A cover 11 forms a closure for the top of the hopper 10 and is provided with latching means indicated generally at 12, for securing the cover 11 in position. The bottom of the hopper is constituted by a semi-spherical stamping 13 which may be integral with the upper portion, or secured thereto as by crimping 14. 60 The bottom of the portion 13 is provided with a centrally apertured boss 15 which serves as a bearing for an agitator shaft 16. The shaft 16 is polygonal intermediate its ends as at 17, and a plurality of sheet metal 65 blades 19 are secured together in such a manner as to form a polygonal hub 20 which receives the shaft 17. The blades 19 are preferably of circular contour so as to just clear the inside of the semi-spherical portion 13. 70

For supporting the upper end of the shaft 17, a substantially triangular plate 21 is provided, portions of which are crimped around radially extending rods 22. The plate 21 75 has a central aperture through which projects a hollow cylindrical bearing member 23, having an external shoulder 24 which engages the plate 21. The reduced portion of the member 23 is threaded as at 25, to receive a cap 27 which carries a plug 28 80 slidable in the bore of the member 23 and provided with a conical end 29 which is adapted to engage the inner ends of the rods 22 and cam the same outwardly so as to fit 85 in a circular groove 30 formed in the hopper 10. This arrangement permits the entire upper bearing member to be assembled outside of the hopper, and to be mounted therein 90 by merely turning the cap 27. 95

The bottom of the member 23 is provided with a central aperture 31 which receives the rounded upper end of the shaft 17 and forms a bearing therefor. The shaft 17 carries a 5 circular rack 32, comprising a hollow frusto-conical sheet metal member, the lower base 33 of which has a polygonal aperture to engage the shaft 17, and the upper base 34 of which is provided with a circular aperture 10 to receive the rounded end of the shaft. The circular rack 32 meshes with a lantern wheel 35 carried by a shaft 36 which is rotatable in a tube 37 projecting through the hopper 10. A sheet metal bracket 38 is secured at one end to the inside of the casing and at the other end to the inner end of the tube 37.

A flared sheet metal outlet member 40 is secured to the semi-spherical portion 18, 20 which is cut away as at 41 to permit communication therebetween. The member 40 is provided with a depressed portion 42 to enclose and provide clearance about the lower end 16 of the shaft 17.

25 Associated with the hopper 10 is a fan casing 45, provided with a cover 46. The casing 45 is a cylindrical cup-shaped member having a similar cup-shaped portion 47 formed therein. A plate 26 separates the 30 portion 47 from the fan chamber so as to form a mixing chamber, and this plate is notched to permit passage of dust and air therethrough. The portion 47 engages a flange 48 formed on the outlet member 40 35 and is secured thereto as by machine screws 49. The face 50 of the portion 47 forms a partition between the hopper and the fan casing. The partition is provided with a dust aperture 51 which is spaced from, but 40 concentric with respect to, a central aperture 52 through which passes a fan shaft 54 carrying a fan 55. The fan 55 comprises a plurality of sheet metal blades secured together to form a hub 56 which is fastened to the 45 shaft 54 by a set-screw 57.

Secured to the cover 46 is a gear casing 58 comprising two halves formed of sheet metal and crimped or otherwise secured together. The shaft 54 passes through registered apertures in the cover 46 and casing 58 and terminates in an anti-friction bearing 60. A pinion 61 is keyed to the shaft 54 and is driven through intermediate reduction gearing 62 with a ratio of 62.2 to 1, from a 55 drive gear 63 keyed on a drive shaft 64 journaled in the gear casing 58. The shaft 64 may be driven by any desired source of power, a hand crank 65 being shown for this purpose, and the gear ratio may be modified 60 as desired.

As shown in Fig. 2 the shaft 64 projects through the gear casing 58, and a length of coiled spring 66 forms a flexible drive connection between the shaft 64 and the shaft 36 65 for driving the agitator in the hopper.

Referring now to Fig. 6, a tube 70 is mounted in the aperture 52 and is provided with a flange 71 to which is secured a plate 72 having a slot 73 formed therein and adapted to cooperate with the dust aperture 51 and form 70 a valve therefor. As shown in Fig. 5, the slot 73 has a narrow arcuate portion 74 and a wider arcuate portion 75. The plate 72 is mounted on the side of the partition 50 toward the hopper 10. The end of the tube 75 70 inside the partition 50 is formed into a cup 59 containing a fiber washer 53 forming a bearing for the shaft 54 and a felt washer 43 which prevents passage of dust to the bearing washer 53. An arm 77 is rigidly 80 secured to the tube 70 by means of a cover member 44 which is pressed over the cup 59, which completes the casing for the washers 43 and 53. The arm 77 extends upwardly 85 through one of a plurality of inlet apertures 76 formed in the wall 47 of the mixing chamber, and forms an indicator which cooperates with a graduated scale 78 secured to the periphery of the fan casing 45.

The shaft 54 terminates inside the outlet 90 40 clear of the agitator blades 19. Threaded on the inner end of the shaft 54 is a cap member 79, which has a cylindrical portion 80 adapted to overlie the end of the tube 70. The cylindrical portion 80 becomes packed 95 with dust, which is retained therein by centrifugal force due to rotation thereof, and prevents more dust from entering between the tube 70 and the shaft 54. The portion 80 carries a whipper 81 which disrupts the 100 dust in the annular channel swept through by this member. The outer portion of the cap 79 is provided with a paddle 82 which is adapted to urge dust toward the whipper 81 and the aperture 51. A lock screw 83 serves 105 to secure the cap 79 on the shaft 54.

It should be noted that the device as described may be readily disassembled for overhaul by merely removing the screws 49 and disconnecting the flexible drive connection 110 66, so that the driving parts may be entirely removed from the hopper. A hook 83 and a ring 86 are adapted to receive a strap or the like for supporting the duster from the body of the operator.

The casing 45 is adapted for multiple tangential delivery of the dust and for this purpose the casing is cut away to provide an outlet aperture, and an outlet member 85, constructed of sheet metal, is secured to the 120 casing so as to register with the outlet aperture, and to extend tangentially forward from the casing 45. A similar outlet aperture, preferably diametrically opposite, is provided with a similar outlet member 87 125 which extends tangentially rearward from the casing 45. A discharge tube 88 is adapted to be connected to either of the outlet members 85 and 87, and a cap 89 is provided for closing the other outlet member. In this 130

manner, the duster is adapted for either forward or rearward delivery of the dust.

However the present invention is not limited to a single discharge outlet, as a discharge tube 88 may be fitted to each of the members 85 and 87, for simultaneous operation. Furthermore a larger number of outlet members may be provided for simultaneous multiple delivery, and this feature is of particular advantage with tangential delivery, because it effects an economy of power. When there is a single tangential delivery, the fan is operating against air friction resistance at all other parts of the casing periphery, and the power thus dissipated is utilized for projecting dust, when further tangential outlets are provided.

In operation, the latching mechanism 12 may be unlatched and the cover 11 opened so that a supply of dust may be inserted into the hopper 10. The arm 77 will then be adjusted so that the indicator corresponds to the graduation of the scale 78 which is prescribed as giving the proper aperture for the type of dust being distributed, and the best use for which the dust is being employed. The crank 65 will then be rotated to drive the shaft 64 through the flexible driving connection 66 and shaft 36 and drive the shaft 17 and thus rotate the agitator blades 19 at a lower speed, such as substantially one-fourth of the speed of the shaft 64. This operation will prevent caking or packing of the dust in the hopper 10 and insure that the dust will pass through the aperture 41 through the outlet 40.

The rotation of the shaft 64 as described above will drive the gear 61 from the gear 63 through the gearing 62 and thus rotate the shaft 54 at a greatly increased speed. The whipper 82 being carried by the shaft 54 will urge the dust from the hopper aperture 41 outwardly through the outlet 40 in the direction of the dust aperture 51 in the partition 50. The fan 55 will also be rotated at the same speed and will draw air in through the apertures 76. The dust will pass through the slot 73 into the chamber 47 where it is mixed with the air and passes in a cloud through the fan and out through one or more of the outlets 85 or 87, depending upon whether multiple or forward or rearward delivery is selected.

While one embodiment of the invention has been illustrated and described in such detail as to enable any one skilled in the art to practice the invention, nevertheless it will be understood that the invention is not to be limited to any of the details disclosed, other than as necessitated by the development of the prior art; but, instead, the invention embraces such embodiments of the broad idea as fall within the scope of the appended claims, it being obvious that various substitutions, modifications and other changes may

be made with respect to the disclosed embodiment without departing from the spirit of the invention.

Having thus described my invention, I claim:

1. In a duster, a hopper, an agitator in said hopper, an aperture in said hopper, a unit detachably connected to said hopper adjacent said aperture comprising a casing, a fan in said casing, drive mechanism carried by said casing for driving said fan, and a detachable driving connection from said drive mechanism to said agitator.

2. In a duster, a hopper, an agitator in said hopper, a fan casing attached to said hopper, a fan in said casing having a shaft extending into said hopper, a shaft projecting laterally from said hopper for driving said agitator, a common drive shaft spaced from said fan shaft, means for driving said fan shaft from said common drive shaft, and a flexible detachable connection between said common drive shaft and said agitator driving shaft.

3. In a duster, a hopper, an agitator in said hopper, a fan casing attached to said hopper, a fan in said casing, a drive casing attached to said fan casing, a drive shaft journaled in said drive casing, means in said drive casing for driving said fan from said drive shaft, and means outside of said casing for driving said agitator from said drive shaft.

4. In a duster, a partition having an aperture therein, means for supplying dust to one side of said partition, a shaft passing through said partition, a plate rotatable about said shaft and engaging the dust compartment side of said partition, a slot in said plate to cooperate with said aperture, and means for rotating said plate about said shaft to vary the area defined by registering portions of said slot and aperture.

5. In a duster, a hopper having an outlet, a fan casing connected to said outlet, a fan in said casing having a shaft extending into said outlet, and a whipper carried by said shaft in said outlet.

6. In a duster, a hopper having an outlet, a fan casing connected to said outlet, a partition between said outlet and said fan casing and having an aperture therein, a fan in said casing having a shaft extending through said partition, a plate rotatable about said shaft on the hopper side of said partition and having an arcuate slot therein with portions of stepped widths to cooperate with said aperture, an arm on the fan side of said partition for moving said plate to vary the area defined by registering portions of said slot and aperture, and a graduated scale on the outside of said fan casing to cooperate with said arm for indicating values proportional to said area.

7. In a duster, a hopper, a central shaft in

15 said hopper and having an end bearing in the wall thereof, and a bearing member for the opposite end of said shaft, rods arranged radially of said bearing member for supporting the same from said wall, means in said wall to receive the outer ends of said rods, and means carried by said bearing member and engaging the inner ends of said rods for camming the outer ends into said receiving 20 means.

In testimony whereof, I hereunto affix my signature.

RALPH R. ROOT.
